(57) **CLAIM**

The ornamental design for a phone case, as shown and described.

DESCRIPTION

FIG. 1 is a first perspective view of a phone case showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the phone case thereof;

FIG. 10 is an enlarged view of the selected portion 10 in FIG. 1; and,

FIG. 11 is an enlarged view of the selected portion 11 in FIG. 9.

The dash-dash broken lines shown in the drawings depict portions of the phone case that form no part of the claimed design. The dot-dash broken line squares and lead lines in FIGS. 1, 9, 10, and 11 are included for the purpose of delineating the portions shown in the enlarged views and form no part of the claimed design.

1 Claim, 11 Drawing Sheets
